UNITED STATES PATENT OFFICE

170,979

HANDBAG

William H. Hardy, River Edge, N. J.

Application August 7, 1953, Serial No. 26,349

Term of patent 7 years

(Cl. D87—3)

To all whom it may concern:

Be it known, that I, William H. Hardy, a citizen of the United States, residing in River Edge, in the county of Bergen and State of New Jersey, have invented a new, original, and ornamental Design for a Handbag, of which the following is a specification, reference being had to the accompanying drawing, forming part thereof.

Fig. 1 is a top plan view of a handbag showing my new design,

Fig. 2 is a front view of the handbag,

Fig. 3 is the rear view of the handbag,

Fig. 4 is the end view of the handbag, and
Fig. 5 is an open top view thereof.

I claim:

The ornamental design for a handbag, as shown.

WILLIAM H. HARDY.
